IGNITION DEVICE

Mayer L. Goldman, Baltimore, Md., assignor to
 May Oil Burner Corporation, Baltimore, Md.,
 a corporation of Maryland

Application February 10, 1931, Serial No. 514,863

11 Claims. (Cl. 175—115)

The invention relates to an electrical ignition device.

In the particular adaptation of the invention herein disclosed and described, it is shown in connection with a hydrocarbon burner for heating systems. The device can be utilized wherever it is necessary to ignite liquid, gaseous, or pulverized fuel, and it is strictly understood that the invention is not limited particularly to the present disclosure.

Electrical devices to ignite liquid, gaseous or pulverized fuel have been heretofore used with questionable satisfaction, and there have been apparent several defects which depreciate the practicability of the ignition devices. To elucidate more particularly, the primary functions of the electrical ignition devices, namely, unfailingly providing a spark of sufficient intensity to cause ignition, and positioning the spark at a point relative to the fuel stream where failure to ignite is impossible, appears in the majority of instances to be lacking. Research and experiment of electrical ignition devices heretofore used has revealed that, while it is usually possible to provide an intense spark in a position relative to the fuel stream, it has not been possible to eliminate the damaging results often encountered through the burning of the electrode tips through overheating, and of more importance the formation of carbonaceous deposits on the electrodes which eventually will bridge the gap between the electrodes and defeat the purpose of the device. Such results entail the renewal of the electrode tips or at least disassembling of the entire ignition device, in order to clean the electrodes, and may be the cause of more or less violent explosions, due to unignited fuel collecting within the combustion chamber and being thereby irregularly ignited.

It is customary to so time the duration of the flow of the electric current producing the spark that it will cease to be operative after the lapse of a fixed and predetermined time from its initiation. My device is so actuated that it functions to withdraw the electrodes or electrode from their positions relative to the fuel outlet at the time at which the igniting current ceases to flow.

In the use of such fuel burners, especially of the automatic or semi-automatic control type, it has been found necessary, insofar as possible, to safeguard the property adjacent the burner from leakage, fire, or other hazard. To attain this end, I use in my device, a multiple electrode system whereby when the usually operative electrodes or electrode are withdrawn from juxtapo-

sition with the fuel, a secondary set takes the place of the primary set, so that, if by any chance the mechanism should become inoperative, there shall always be one set of electrodes in proper position to ignite the fuel. Thus, in intermittent operation, when by automatic control, the flame is alternately burning and not burning, the electrodes are always in readiness to ignite the fuel at the instant the burner starts to operate. Even though the mechanism fail or the usually operative set of electrodes is not in normal position, there will always be one set of electrodes so positioned that it will be ready to function and to ignite the fuel.

It is one of the objects of my invention to provide an electrical ignition device which will, at the instant the burner starts to operate, supply a spark of intensity sufficient to ignite the fuel.

Another object of my invention is to provide an electrical ignition device which will apply the spark within the radius of fuel stream and to assure its being applied invariably.

Another object of my invention is to provide an electrical ignition device which will, through its mode of operation, reduce to a minimum the formation of carbonaceous deposits on the electrodes, and eliminate entirely the burning of the electrode tips and the possibility of carbonaceous deposits bridging the gap between the electrodes.

Another object of my invention is to provide an electrical ignition device which is controlled automatically, simple, yet durable in construction and of great practical value, particularly when used in connection with hydrocarbon burners in heating systems.

Still another object of the invention is to provide an electrical ignition device which can be economically manufactured.

With these and other objects and advantages in mind, attention is called to the drawings, in which:

Figure 1 is a side elevation of the hydrocarbon burner, showing the relative position of the electrical ignition device to the other parts of the burner.

Figure 2 is a side elevation of the electrical ignition device and atomizer head with the solenoid not energized.

Figure 3 is a plan view of the atomizer head and electrodes.

Figure 4 is a sectional view taken on the line 4—4 of Figure 2.

Figure 5 is a sectional view taken on the line 5—5 of Figure 2.

Figure 6 is a perspective view of the atomizer head and electrodes.

Figure 7 is a detail view of the operative connection between the linkage members of the sole-noid and the movable electrodes.

Figure 8 is a detail view of another form of operative connection between the linkage members of the solenoid and the movable electrodes.

Figure 9 is a side elevation of a modified form 10 of the device.

Figure 10 is a plan view of the modified form or the device in Figure 9.

Figure 11 is a front end view of the modified form of the device in Figure 9.

15 Figure 12 is a diagrammatic view of the electrical wiring and control of the ignition device and burner.

Referring specifically to the drawings, in which like numbers indicate like parts, it will be noted 20 in Figure 1, the disclosure of the entire burner on which the electrical ignition device forms a part, there is shown relative thereto a wind pipe 1 having positioned adjacent thereto a blower 2. An end cap 3 fits over one end of the wind pipe and is 25 secured thereon by means of a slot 4 and projection 5. There is a similar slot and projection diametrically opposite to the one shown.

A fuel supply pipe 6 is held centrally of the wind pipe by means of the end cap 3 and a guide 30 member 7 positioned near the front end thereof. The fuel supply pipe is secured to an end fitting 8 which is secured by means of a union 9 to the valve 10 positioned thereabove.

35 A remote control, such as a thermostat 11, is in electrical connection with a control relay 12 which is in electrical connection with an ignition transformer 13 and a solenoid 14. The various 40 circuits and the operation thereof between the parts designated above will in detail later be described.

The guide member 7 comprises four radial helical arms which abut against the wind pipe and serve to agitate or turbulate the air stream. The two upper arms form holding brackets for 45 portions of the electrode mechanism. The atomizer head 15 is screw threaded or otherwise attached to the fuel supply pipe.

A bracket 16 is adjustably secured to the fuel pipe and has two upwardly extending guide arms 50 17 and 18, as shown in Figure 4. A second bracket 19 having a single guide arm 20, is adjustably secured to the fuel pipe adjacent the guide member 7, as shown, or may be integral with the said guide member.

55 An electrode rod 21 passes through and is adjustably held between the guide arm 17 of bracket 16 and one of the upper radial arms of guide member 7. Insulators 22 are provided between the electrode rod and brackets, and an 60 electrode tip 23 bends toward the orifice of the atomizer head so that its position will be within the radius of the fuel stream. Electrode rod 21 is the current bearing electrode and is in electrical connection with the ignition transformer 13.

A rod 24 passes through and is slidably held 70 between the guide arm 18 of bracket 16 and the guide arm 20 of brackets 19. Abutting the guide arm 18 to the rear thereof and surrounding the rod 24, is a washer 25 between which and an adjustable collar 26 is positioned a spring 27. At the front end of the guide arm 18 and encircling the said electrode rod 24, is an adjustable collar 28, which is provided with a notch or recess 29 in the top thereof. A suitable non-

5 metallic shock absorbing and noise preventing washer is provided at 30. Secured to the front end of the rod 24 is a forked member 31 in which movably mounted in any suitable manner, such as a pivot pin 32, is a linkage member 33, the front end of which is movably secured in any suitable manner, such as a pivot pin 34, to an electrode holder 35. The electrode holder 35 carries the ground electrode as will be herein-after described.

10 The electrode holder 35 is hinged to a member 36, as at 37, said member 36 being secured to a ground electrode rod 38, which is adjustably held by one of the radial arms of the guide member 7. It will be noted that the electrode holder 35 is cut away at 39, and will abut against portion 40 of member 36 when the rod 24 is actuated, thereby limiting and defining the movement or oscillation of the said electrode holder. Attention is also called to the fact that the 20 ground electrode rod 38 is adjustable relative to the radial arm of the guide member 7, thereby facilitating the positioning of the electrode holder relative to the atomizer head.

25 Two electrode portions 41 and 42 with tips 43 and 44, respectively, comprise the ground electrode and are adjustably secured to the electrode holder 35. The said electrode portions are bent inwardly and downwardly toward the atomizer head and the electrode tip 44 is bent upwardly 30 at substantially right angles.

When the device is in inoperative position, therefore, there exists a sparking gap between the angle in the electrode tip 44 and the electrode tip 23. If, then, the rod 24 is actuated, 35 the entire length of the bent-up portion of the electrode tip 44 will pass the electrode tip 23 at a sparking gap and when finally the gap is broken, the electrode tip 43 will then move to a position to form a sparking gap with electrode 40 tip 23.

Positioned above the wind pipe and in any suitable manner, is a solenoid 14 having an electrical connection 45. The armature 46 is connected by a link 47 to a lever 48 which is pivoted at 49. Secured to 48 at the said pivot point is a recessed member or lever 50 positioned in such a manner that levers 48 and 50 form a rigid bell crank and lever 50 passes through an aperture 51 in the top of the wind pipe and loosely, 50 but operatively, engages the notch or recess 29 on the adjustable collar 28.

In Figure 8, there will be noted another form 55 of operative connection between the linkage members of the solenoid and the movable electrodes, wherein there are provided notches or recesses 29 on two sides of the adjustable collar 28. The member 50 is more deeply recessed to loosely, but operatively engage the notches or recesses 29.

In Figures 9, 10 and 11, there will be observed 60 a modified form of the invention, wherein there is used a stationary current bearing electrode, as in the main form, and a movable electrode holder 52, to which is secured but a single electrode tip 53.

The movable electrode tip 53 is formed in substantially hook-shaped manner and is bent to provide an elbow at spaced distance from the end of the tip, as shown in Figures 9 and 10, 75 thus providing a pair of active electrode portions depending upon the position of the tip 53, which in turn depends on the position of the rod 24. When the electrode tip 53 is in retarded position as disclosed in Figure 9, the end of the 75

tip will still be in spaced arcing position with respect to the fixed electrode 23. When the operating rod 24 is actuated to move the electrode tip 53 downwardly, the end of the same will move past the end of the stationary electrode 23, and the elbow in the tip 53 will come into spaced arcing position with respect to the end of the fixed electrode 23. Thus, during the entire movement of the movable electrode, one of its portions will be in spaced arcing relation with respect to the fixed electrode 23, and it will also be observed that if the movable electrode is in retarded position, and the actuating mechanism for the same fails to function, nevertheless, the burner may be ignited by the arc which will be enabled to pass from the fixed electrode to the end of the movable electrode 53.

Referring to Figure 12 of the drawings, there will be noted a wiring diagram for the various electrical circuits which operate the ignition device. The source of electrical energy is introduced through the circuits at A, and is connected to the remote control, such as the thermostat 11. When the contact of the remote control is closed, the coil of the control relay 12 is energized and causes the contact therein to close. Upon the closing of this contact the primary coil of the ignition transformer 13 is energized and the current traverses the current bearing electrode 21 and at the same instant the solenoid 14 is energized to operate the recessed member 50, and consequently the movable electrodes 41 and 42 of the ground electrode 38. This movement of the said recessed-member places the electrode tip 43 in true ignition position, and a sparking occurs between the movable electrode tip 43 and the current bearing electrode tip 23. However, it must be understood that should the mechanism fail to place the electrode tip 43 in operative ignition position with respect to the electrode tip 23, sparking will, nevertheless, occur between electrode tip 44 and electrode tip 23 at any time either during or before the movement when the spark coil is operating, and until such time as the electrode tip 43 comes within operative sparking range with respect to electrode tip 23.

When the primary coil of the ignition transformer is energized, a high voltage is set up in the secondary winding of the transformer. One side of the high voltage winding is connected to the ground B. The frame of the transformer being attached to the base plate of the burner is in electrical contact therewith, and, consequently, a ground circuit is carried through the various parts of the burner to a point C, where it comes into contact with the ground electrode 38. The other terminal of the secondary winding of the transformer is connected directly to the current bearing electrode 21, which is insulated from all other parts of the burner to the spark gap.

When the current is cut off from the ignition transformer by operation of the control relay, the solenoid is deenergized and the movable electrodes are drawn to their original position by means of the spring 27. The current bearing electrode is deenergized at the same instant and the spark ceases at the spark gap.

It will thus be seen that due to the movable electrodes and the operation thereof, that the possibility of carbonaceous deposits bridging the gap between the electrodes is entirely eliminated, since each movement of the movable electrode will break any carbonaceous deposit between the movable and stationary electrode tips and will

tend to dislodge carbonaceous deposits on each of said tips.

If, for any reason, the electrodes fail to move, the spark will, nevertheless, be provided at the gap formed by the current bearing electrode tip 23 and the angle in the electrode tip 44 of the electrode 42 of the ground electrode 38. The same is true in respect to the modified form shown in Figures 9, 10 and 11.

It is obvious that either a grounded or ungrounded system of electrical circuits may be used in the operation of the device.

Attention is called to the accessibility of the ignition device. By simply unscrewing the union 9 from the fuel pipe and turning the cap 3 and disengaging it from the wind pipe 1, the atomizer head, supply pipe and ignition device may be dropped to disengage the recesses 29 on the main form or recesses 29 of the form shown in Figure 8 on the adjustable collar 28 from the recessed member 50 and subsequently withdrawn from the wind pipe. In this way, any repairs, replacements or adjustments may be quickly made to the ignition device or atomizer head without disassembling the entire burner.

It is obvious that there are various changes and modifications which can be made to the structure described without departing from the scope of the appended claims.

I claim:

1. An ignition device for fuel burners comprising a stationary electrode, a plurality of movable electrodes, and means for effecting relative advance and return movements of said movable electrodes along the same path adjacent the stationary electrode one or the other of said movable electrodes being in spaced arcing position with respect to said stationary electrode at all times during the movements of said movable electrodes.

2. An ignition device for fuel burners comprising a stationary electrode, a plurality of movable electrodes, means positively to effect advance movement of said movable electrodes, and means to effect return movement of said electrodes along the same path adjacent the stationary electrode one or the other of said movable electrodes being in spaced arcing position with respect to said stationary electrode at all times during the movements of said movable electrodes.

3. An ignition device for fuel burners comprising a stationary electrode, a plurality of vertically spaced movable electrodes, means positively to effect advance movement of said movable electrodes, and means automatically to effect return movement of said electrodes along the same path adjacent the stationary electrode one or the other of said movable electrodes being in spaced arcing position with respect to said stationary electrode at all times during the movements of said movable electrodes.

4. In an ignition device for burners, a burner tip for projecting fuel, a pair of cooperating electrodes positioned in spaced arcing relation with respect to each other adjacent the fuel stream from said burner tip, electric means for causing an arc between said electrodes, and means for moving one of said electrodes away from the other.

5. An ignition device for burners comprising a burner tip for projecting fuel, a stationary electrode positioned adjacent the fuel stream from said burner tip, a movable electrode, and means for moving said movable electrode into spaced arcing position with respect to said fixed elec-

trode and for moving the same away from said fixed electrode.

6. An ignition device for burners comprising a stationary electrode, a movable electrode, and means for moving said movable electrode between advanced and retarded positions with respect to said fixed electrode, said movable electrode having a portion in spaced arcing position with respect to said fixed electrode when said movable electrode is in retarded position, and another portion in spaced arcing position with respect to said fixed electrode when said movable electrode is in advanced position.

7. An ignition device for burners comprising a stationary electrode, a movable electrode, and means for moving said movable electrode between advanced and retarded positions with respect to said fixed electrode, said movable electrode having a portion in spaced arcing position with respect to said fixed electrode when said movable electrode is in retarded position, and another portion in spaced arcing position with respect to said fixed electrode when said movable electrode is in advanced position, one of said portions being in arcing position with respect to said fixed electrode at all times during the movements of said movable electrode.

8. An ignition device for burners comprising a stationary electrode, a movable electrode holder carrying a plurality of movable electrodes, and means for moving said holder between advanced and retarded positions with respect to said fixed electrode, one of said movable electrodes being in spaced arcing position with respect to said fixed electrode when said holder is in retarded position, and another of said movable electrodes being in spaced arcing position with respect to said fixed electrode when said holder is in advanced position.

9. An ignition device for burners comprising a stationary electrode, a movable electrode holder carrying a plurality of movable electrodes, and

means for moving said holder between advanced and retarded positions with respect to said fixed electrode, one of said movable electrodes being in spaced arcing position with respect to said fixed electrode when said holder is in retarded position, and another of said movable electrodes being in spaced arcing position with respect to said fixed electrode when said holder is in advanced position, one of said movable electrodes being in arcing position with respect to said fixed electrode at all times during the movements of said holder.

10. An ignition device for burners comprising a stationary electrode, a movable electrode provided with an elbow spaced from its outer end, and means for moving said movable electrode between advanced and retarded positions with respect to said fixed electrode, the outer end of said movable electrode being in spaced arcing position with respect to said fixed electrode when said movable electrode is in retarded position, and the elbow of said movable electrode being in spaced arcing position with respect to said fixed electrode when said movable electrode is in advanced position.

11. An ignition device for burners comprising a stationary electrode, a movable electrode provided with an elbow spaced from its outer end, and means for moving said movable electrode between advanced and retarded positions with respect to said fixed electrode, the outer end of said movable electrode being in spaced arcing position with respect to said fixed electrode when said movable electrode is in retarded position, and the elbow of said movable electrode being in spaced arcing position with respect to said fixed electrode when said movable electrode is in advanced position, either the elbow or the end of said movable electrode being in arcing position with respect to said fixed electrode at all times during the movements of said movable electrode.

MAYER L. GOLDMAN.
